UNITED STATES PATENT OFFICE.

CHRISTINE PETERSEN, OF CHICAGO, ILLINOIS.

COMBINED CORSET AND BRASSIÈRE.

Application filed July 19, 1926, Serial No. 123,396. Renewed November 14, 1928.

This invention relates to a combined corset and brassière, the corset being also provided with an abdominal supporting device.

The modern corset is worn rather well down on the body, in such manner that the lower part envelopes the hips and abdomen and the result of this has been that excess flesh or fat has been forced downwardly, producing an undesirable bulge at or about the lower part of the abdomen and a great pressure on the pelvic organs. By means of the present invention, this objectionable condition is avoided, while, however, retaining the desirable features of a comparatively straight line corset, and at the same time restraining and confining pronounced diaphragms. The advantages of an abdominal supporting corset are also retained or provided for, and the whole forms an article which may be worn with comfort and the desired appearance even by stout women.

The existence of the bulge referred to, at or about the bottom of the corset, is recognized by all wearers of the modern corset, and the present invention has been produced largely with the intention of correcting this condition, which is often uncomfortable, unfashionable, and unsightly.

A further noticeable feature of the invention is that the corset may be put on in a "step-in" manner, without undoing any laces, this action being permitted by a slit in the upper part of the corset front which is fastened by hooks and eyes which may be detached to allow sufficient expansion for the corset to be drawn up over the body into proper position. Or, it may be put on over the head. This avoids the trouble of hooks and eyes and permits an adjustment to be made which does not have to be disturbed. It also avoids the lumps produced by hooks and eyes which can often be seen thru the outer garments.

The invention is illustrated in the accompanying drawings, in which Fig. 1 is a front view of one form of the invention with the corset closed or laced up. Fig. 2 is a similar view with the corset laid open to expose the inner parts or arrangement. Fig. 3 is a partial side view showing an elastic section as well as the connection between the brassière attachment and a tab on the side of the corset. Fig. 4 is a front view of a modification, the brassière attachment consisting of a single piece instead of two overlapped pieces.

In the drawings, two front sections of the

corset proper are indicated at 6 and 7, and a back section indicated at 8. The latter may be provided with stiffeners 9 inserted in casings therein and extending from a point a few inches from the bottom edge to a point a few inches from the top edge. The front edges of the front pieces are connected by laces, extending thru eyelets in the reinforced edges, and if desired two sets of laces may be used, an upper set indicated at 10 and a lower set indicated at 11, and the latter may be elastic, if desired, and will preferably be made so. Or, a single set of laces may be used extending from the top to the bottom of the corset proper.

The front pieces 6 are connected to the back piece 8 by elastic sections 12, made of elastic fabric sewed to the adjacent pieces, and these elastic sections will expand or contract as occasion demands, thereby forming a very flexible corset.

It will be noticed that the back section 8 extends up considerably higher than the front sections 6 and 7 of the corset, said back extension forming in effect a back section of a brassière, the lower part of the back section forming in effect the back of the corset.

In the form shown in Figs. 1 and 2, the brassière is completed by means of two overlapping front sections 13 and 14, which are somewhat triangular in shape and which are intended to cover or fit around the bust and confine the diaphragm, and are adjustable independently of the corset sections below. At the front, they lap to some extent the upper ends of the front sections 6 and 7. The sections 13 and 14 are sewed to the back piece 8 at points on the side of the corset under the arm pits, and the elastic sections 12 are located in substantially the same line, that is, lines at the side of the body under the arm pits. The free ends of the brassière pieces 13 and 14 are fastened by laces 15 to tabs 16 sewed to the rear edge of the pieces 6 and 7, conveniently at the junction line with the elastic sections 12. The laces 15 extend thru eyelets in the ends of the brassière sections and corresponding eyelets in the tabs. Shoulder straps 17 may be attached to the brassière sections, and hose supporters 18 to the front and back corset sections.

In the form shown in Fig. 1, the brassière section 13 laps over the brassière section 14 and the former is provided with a loop 19 at the middle line, and the latter is provided with a strap 20 corresponding in position,

the strap being provided with a hook 21, and when the garment is worn, the hook 21 and strap 20 are slipped thru the loop 19 and the hook is then engaged with one of the 5 laces 10, thereby holding the brassière sections down at the front and giving a smooth appearance and a close fit over the bust and diaphragm.

Associated with the corset is an abdominal supporter of known construction, comprising two pieces 22 which are fastened at their upper rear ends to the edge of the back piece 8 and are connected at their lower front ends by means of laces 23 10 extending thru eyelets in the adjacent ends, and when the corset is worn, the supporters sustaining all pressure downwardly on the vital organs below and assist in supporting the abdominal organs. The adjustment of 15 the laces 23, it may be noted, is independent of the adjustment of the corset section and the brassière sections. Thigh straps 24 may be used in connection with these abdominal supporting sections, if desired. It will be noticed 20 that the strain on the abdominal supporter is transmitted around the sides of the body to the back piece 8 to which, as stated, the rear ends of the abdominal supporters are fastened.

30 To enable the garment to be put on without unloosing the laces, I provide in one of the sections 6 or 7 (7, as shown), a slit 25 which extends a few inches from the top thereof, near the front edge, and this slit 25 may be 35 opened or closed by hooks and eyes 26. When the corset is to be put on, these hooks and eyes may be unfastened to give sufficient expansion for the garment to be drawn up or down over the body without undoing the 40 laces 10 and 11 which can thus be left at ad-

justment. The laces 10, which confine the body in the vicinity of the diaphragm, can be adjusted tight enough to prevent any bulging of flesh at this point, and above this the brassière sections may be worn as tight or 45 as loose as desired, in consequence of the adjustment permitted by the laces 15. The combined garment thus takes care of any objectionable conditions incident to compression of the various parts of the body without any objectionable bulging or irregularities of the desirable straight line outline. 50

In the modified form shown in Fig. 4, instead of forming the brassière of two crossed pieces 13 and 14, it consists of a single 55 piece 30, which may be sewed to one edge of the back 8 as indicated at 31 and is provided at the other end with a row of hooks 32 engaging a row of eyes 33 secured to the back section under the arm pit. After the corset is 60 adjusted, this brassière section 30 may be laid over the bust and fastened for the intended purpose.

The construction is optional in many respects, and no limitation is intended by reason of the particular forms or devices shown and described. 65

I claim:

A combined corset and brassière comprising a pair of front corset pieces, a back piece 70 extended upwardly beyond the front pieces, elastic sections between the front and back pieces, tabs connected to the front edges of the elastic sections, and a pair of crossed brassière sections fastened at one end to the 75 side edges of the upper part of said back piece and adjustably connected at their free ends to said tabs.

In testimony whereof, I affix my signature.
CHRISTINE PETERSEN.
